UNITED STATES PATENT OFFICE

ALEX DE SCHEBEKO, OF CHICAGO, ILLINOIS

TOOL

Application filed January 27, 1932. Serial No. 589,141.

My invention relates in general to tools. It relates more in particular to a tool for picking up and holding various small objects, usually objects of a mechanical nature.

In handling small mechanical parts such as small screws, breaker points of an ignition system, small springs, washers and the like, considerable difficulty is encountered by the mechanic especially when working in a relatively confined space. For some classes of small work it has been customary to employ a tool similar to a tweezer, and although this type of tool has some advantage in some classes of work, it is by no means capable of universal application to the handling of small machine parts.

The principal object of my present invention is the provision of an improved tool for handling small parts.

Another object is the provision of a tool of this character adjustable to have great utility in handling different types of parts.

Another object is the provision of the spring crest bi-part tool in which the action of the spring can be changed in accordance with the use to which the tool is put.

Other objects and features of the invention will be apparent from the description of the following details taken of the following drawing:

Fig. 1 is an elevational view of one embodiment of the invention shown in actual size and adjusted for one class of work,

Fig. 2 is an enlarged view of the same tool having a different adjustment,

Fig. 3 is a plan view of the tool as shown in Fig. 2,

Fig. 4 is a substantially full size view showing still another way in which the tool may be adjusted,

Fig. 5 is a transverse sectional view taken along the line 5-5 of Fig. 2, and,

Fig. 6 is a sectional view partly in elevation along the line 6-6 of Fig. 2.

In accomplishing the invention in general I provide a pair of arm members pivoted intermediate the ends, thus providing a pair of arms on each side of the pivot point.

Spring means is provided adapted to be disposed immediately in line with the pivot

point so that the arm members will move freely on the pivot, or on either side of the pivot point so that one pair of arms will be spring pressed together and may be separated against the spring tension by squeezing the opposite pair of arms.

Referring now to the drawing:

I provide arm members 10 and 11, the arm member 10 having arms 12 and 13 and the arm member 11 having arms 14 and 16. The arm member 10 has a center projection 17 intermediate its ends relatively thinner than the main body of the member and disposed to cooperate with a similar projection 18 on the arm member 11 to form pivoting means. Each of these members 17 and 18, lying side by side when the tool is assembled is apertured to receive the shank of a pivot member 19. A machine screw 21 having a washer 22 cooperates with the pivot No. 19 to form a complete pivot assembly as shown in Fig. 5. Thus the two arms are pivoted together intermediate therein to have free pivotal movement, but the pivot is secured so that when the arms come together the points thereof will coincide accurately.

For the spring means for controlling the action of the arm members, I provide transverse pins 23 and 24 connected together by springs 26 and 27. These pin members are disposed transversely over the two arm members and are adapted to be held in any pair of a number of depressions 28-28 on the outer edges of the two arm members. The springs are of such a length and so disposed with respect to the arms that they are under tension at all times.

The ends of the arms may have any suitable shape depending upon the class of work for which the tool is being used. I show, for example, that the gripping ends of the arms 12 and 14 are substantially flat gripping ends; while at the end of the arms 13 and 16 I provide recesses 29 of suitable shape to facilitate gripping round or square objects such as small screws, pins, or other round or odd shaped articles. The arms 12 and 14 being flat are principally adapted for gripping relatively flat articles such as

small leaf springs or the like, but they can, of course, be used to grip articles of any shape.

The uses to which the tool may be put and the manner in which it is used are many, and the manner of operation will differ depending upon specific types of work. I wish to point out, however, that if the spring assembly is positioned in line with the pivot no appreciable tension is applied to either pair of arms and the tool can be used substantially in the way that an ordinary pair of tweezers or similar tool is used. The spring assembly, however, may be moved to either side of the pivot to apply tension to either pair of arms. In Fig. 1 the arms 12 and 14 are under tension while in Fig. 2 the arms 13 and 16 are spring pressed. Looking at Fig. 2, if a small article is to be gripped by the formed ends of the arms 13 and 16, the other pair of arms is brought closer together by pressure, the article to be handled, for example, a small screw, is placed between the ends of the arms 13 and 16 and the hand pressure on the arms 12 and 14 is released. The spring assembly will then hold the arms 13 and 16 together, thus securely holding the screw or other small part between the spring pressed arms.

The tool is of considerable utility in handling relatively small springs for example having loops on their ends which are for example to be engaged over a pair of pins. Such a spring would be similar to the springs 26 and 27 used herein as a part of the tool. In this case with the tool adjusted as shown in Fig. 2 the arms 12 and 14 would be pressed together and the ends of the arms 12 and 14 inserted through the loops at the end of the spring. Pressure on the arms by the fingers would then be released, and a small spring would be expanded and held on the ends of the arms. When the spring was to be placed over a pair of pins then, for example, it would only be necessary to hold the arms 12 and 14 in alignment with the pins or posts for the small spring and then force the small spring off the ends of the arms on to the posts by a suitable tool.

I have disclosed a specific embodiment of my invention, but it is understood that I am not restricted to the specific form shown, the invention being limited only by the scope of the appended claims.

What I claim is new and desire to protect by United States Letters Patent is:—

1. In a tool of the character described a pair of arm members, means for pivoting the arm members intermediate their ends, a spring assembly, and means for supporting the spring assembly in alignment with the pivot or at either side thereof.

2. In a tool of the character described, a pair of arm members having side projections intermediate their ends, a pivot disposed be-

tween the two projections to pivot the members intermediate their ends, a spring assembly disposed around both arm members, and means for supporting the spring assembly on the arm members either in alignment with the pivot or at either side thereof.

3. In a tool of the character described, a pair of arm members, projections on the arm members intermediate the ends, means for pivoting the two arms together at said projections, a spring assembly comprising a pair of pins connected together by a pair of springs, and means for supporting said spring assembly across the two members so that said pins are in alignment with the pivot or at either side thereof.

4. In a tool of the character described, a pair of arm members, projections on the arm members intermediate the ends, means for pivoting the two arms together at said projections, a spring assembly comprising a pair of pins connected together by a pair of springs, and means for supporting said spring assembly across the two members so that said pins are in alignment with the pivot or at either side thereof, said means comprising a plurality of indentations in alignment with each other on each of the arm members.

5. In a tool of the character described, a pair of arm members each having its ends shaped to permit cooperation between the arms at each end of the two members for, grasping a relatively small article, projections on each arm member intermediate the ends thereof, means for pivoting the arm members together at said projections, spring means for pressing the arms together, and means for supporting the spring means in alignment with the pivot or at either side thereof whereby spring pressure is applied to either pair of arms.

6. In a tool of the character described, a pair of arm members each having its ends shaped to facilitate grasping relatively small articles, a relatively thin projection on one of said arm members intermediate the ends thereof, a relatively thin projection on the other arm member positioned to lie along the projection of the first arm member and maintain the two arms in alignment, pivot means for the arm members comprising a member having an internally threaded shank extending through apertures in the two projections, a washer and a machine screw extending through the washer into said internally threaded shank, spring means for pressing the two arm members toward each other, and means for supporting said spring means either in alignment with said pivot or at either side thereof.

7. In a tool of the character described, a pair of arm members each having its ends shaped to facilitate grasping relatively small articles, a relatively thin projection on one of said arm members intermediate the ends

thereof, a relatively thin projection on the other arm member positioned to lie along the projection of the first arm member and maintain the two arms in alignment, pivot
5 means for the arm members comprising a member having an internally threaded shank extending through apertures in the two projections, a washer and a machine screw extending through the washer into
10 said internally threaded shank, a spring assembly comprising a pair of pins, and a pair of springs engaging the ends of the pins, and means for supporting said spring assembly on the arm members so that the pins are in
15 alignment either with the pivot or in alignment at either side of the pivot.

8. In a tool of the character described, a pair of arm members each having its ends shaped to facilitate grasping relatively small
20 articles, a relatively thin projection on one of said arm members intermediate the ends thereof, a relatively thin projection on the other arm member positioned to lie along the projection of the first arm member and maintain the two arms in alignment, pivot
25 means for the arm members comprising a member having an internally threaded shank extending through apertures in the two projections, a washer and a machine screw extending through the washer into said internally threaded shank, a spring assembly comprising a pair of pins, and a pair of springs engaging the ends of the pins, and means for supporting said spring assembly
30 on the arm members so that the pins are in alignment either with the pivot or in alignment at either side of the pivot, said means comprising a plurality of recesses in the arm members.
35

40 In witness whereof, I hereunto subscribe my name this 2nd day of November, 1931.
ALEX DE SCHEBEKO.
